United States Patent

Des. 238,470
Patented Jan. 20, 1976

238,470

WORKBENCH

Kenneth H. Petersen, 821 Index Court NE.,
Renton, Wash. 98055

Original design application Nov. 24, 1971, Ser. No.
202,059, now Patent No. 232,610. Divided and this
application Mar. 4, 1974, Ser. No. 447,999

Term of patent 14 years

Int. Cl. D6—04

U.S. Cl. D6—162

FIG. 1.

FIG. 2.

FIG. 3.

FIG. 4.

FIG. 5.

FIG. 1 is a top plan view of a workbench showing my new design;

FIG. 2 is a bottom plan view;

FIG. 3 is a front elevational view with a right side shelf in extended position, the rear being substantially a mirror image of the front;

FIG. 4 is a front, top and right side perspective view with front, rear and right side shelves and a rear drawer in extended position; and

FIG. 5 is a right side elevational view thereof, the left side being a mirror image of the right.

This is a division of design application Ser. No. 202,059, filed Nov. 24, 1971, now Pat. No. D. 232,610.

I claim:

The ornamental design for a workbench, substantially as shown and described.
